UNITED STATES PATENT OFFICE

WILLIAM J. PETER, OF NEW YORK, N. Y., ASSIGNOR TO AQUA SYSTEMS INCORPORATED,
OF NEW YORK, N. Y., A CORPORATION OF NEW YORK

LIQUID STORAGE SYSTEM

Application filed March 16, 1931. Serial No. 523,013.

This invention relates to a liquid storage system for oil and the like and which is well adapted for use in connection with an overhead or above the ground storage tank having hydraulic or other forms of pumping means for moving the stored liquid to and from the tank, and more particularly relates to non-breather means for storage tanks to eliminate evaporation and consequent loss of volatile oils such as gasoline and the like.

A main object of the invention is to produce novel means in a storage tank system to prevent exhalation of the gaseous vapors from a tank to avoid consequent loss and to prevent inhalation of a charge of fresh air; and such object is better attained when the stored liquid preferably fills the tank to its top, but without undue pressure or force thereagainst, to primarily exclude the air and thus the tank does not have an air space between the liquid surface and at least the greater part of the top of the tank and consequently this portion of the tank cannot breathe. Thus is avoided vaporization and formation of explosive mixtures when storing oil and gasoline, particularly in tanks above the ground. Economy and safety is promoted. This primary object is carried out by compensating for variation in volume of stored liquid by admitting or withdrawing from the tank an amount of displacement liquid equal to the change in volume of the stored liquid.

So called tank breathing results in gasoline and other vapor losses forming from volatile stored liquids and is due to the rise and fall or variation in height of the upper surface of the stored liquid and occurs by operation of two principal causes. This breathing is brought about in one instance largely by night and day or even seasonal temperature variations which expands the liquid in the tank and thus reduces the air space at the top which expels or displaces and hence wastes some of the gas vapors of the stored liquid, and upon cooling of the liquid the contraction thereof conversely increases the volume of the air space at the top of the tank and fresh air is then drawn into the tank to subsequently be expelled and car-

ry off vapor. The repetition of this breathing, due to variation in volume of the liquids, by night and day causes a substantial gasoline loss where the tank is large. Storage tank breathing is also caused in another instance by drawing off the stored liquid for use and then by refilling the storage tank to replenish the stored supply; and these operations, or transference of liquid, causes inhaling and exhaling of the storage tank. After a period of time in which many exhalations and inhalations have taken place due to either cause, temperature variations or liquid transference, the loss of stored liquid is considerable and therefore a reduction or elimination of breathing will bring about a sizable saving in loss of stored liquid.

The main object or purpose above stated is effected by providing novel control means for overhead or above the ground tanks, by which the upper surface of the stored liquid remains at substantially a predetermined level or height, preferably up against the top of the tank, irrespective of the expansion or contraction of the one or more immiscible liquids in the tank due to temperature changes occurring principally by reason of warm days and cool nights or weather conditions.

The main object or purpose above stated is also effected by providing novel control means which maintains the upper surface of the stored oil, gasoline or other liquid at substantially a predetermined level or height, more especially against or in contact with the top of the tank, despite the fact that the volume or quantity of stored oil varies widely due to withdrawal for sale and other use or due to replenishing the stored oil supply. This withdrawal and refilling of a tank may ordinarily be referred to as liquid transfer operations having to do with transferring oil to and from the tank during normal course of business or use of the storage system.

It is also an object to provide novel means, when a hydraulic pumping system is used, to prevent the upper surface of a displacement liquid, such as water under the stored liquid as oil, from exceeding a predetermined

high level or receding below a predetermined low level. If water were permitted to rise above the stored oil outlet pipe located at the top of the tank, it would then be possible to draw off water with the oil, but a control device is employed to prevent the water from reaching the oil delivery pipe leading from the tank. Similarly, it would be possible to drain off oil through the water drain outlet located at the bottom of the tank which usually goes to a waste drain or to the sewer, but to avoid this loss of oil the invention provides means to prevent the lower oil level or surface, which is in contact with the water, from receding to and reaching the water drain.

Another object of the invention is to provide a liquid storage system having a novel float and electrically operated valve means to maintain the upper surface of the oil at substantially a constant predetermined level, or against the top of the tank, and to prevent the upper surface of the water from exceeding a predetermined high or receding below a predetermined low level. In this way a minimum volume of water is retained in the bottom of the tank when said tank is completely filled with oil, and conversely a minimum volume of oil remains in the upper portion of the tank when said tank is filled with water. Thus the adjacent or contacting surfaces of the two immiscible liquids, as shown in the drawing, have limiting levels within the tank, i. e., an upper level and lower level beyond which they do not go. The reference characters HW and LW on the drawing in two positions indicate the two limiting levels of the adjacent surface of the immiscible liquids.

Other objects of the invention will be more apparent from the following description, taken in connection with the accompanying drawing, which illustrates the principles involved and in which:

Figure 1 shows a diagram of the invention and is a section through a storage tank filled with oil to the top and resting on the hydraulic pumping liquid such as water and showing the float controlled electrically operated valve means by which the upper and lower predetermined limiting levels, or adjacent contacting surfaces, of stored liquid and displacement liquid are controlled; and 55 the position of operating parts is such that a valve control means is open in the discharge pipe line for the displacement liquid to flow out because the upper oil surface is abnormally high and hence the automatic control is 60 functioning to lower and adjust the upper oil level.

Figure 2 shows a suitable and well known type of motor-driven opened and closed valve which may be substituted for the solenoid 65 type of operated valve shown in Figure 1.

The motors or solenoids are controlled from the float and switch means on the tank.

Liquid storage systems for storing liquids, such as oils and other liquids which are more or less volatile, have a considerable loss through evaporation when stored in tanks above the ground, and this results from temperature changes throughout the day as well as throughout the seasons when such liquids are stored for any long period of time. Such loss by evaporation occurs even though the storage tank or reservoir is covered since a vent must be provided at the top of the tank and under the varying daily temperatures as well as under the varying temperatures over a longer period, the liquid expands considerably which raises the level of the liquid in the storage tank and this, in turn, reduces the volume of the air space above the liquid. Reduction of the air space above the liquid in the tank forces the evaporated liquid or gas in the air space out of the vent upon the tank. Upon cooling at night time, the liquid contracts which, in turn, increases the volume of space above the liquid in the tank and air is drawn through the vent into the tank. This breathing in and out action is a result of alternate expansion and contraction of the liquid and the evaporated liquids existing as a gas in the space at the top of the tank are continually being lost through the vent in a continuous breathing process.

The storage system herein pertains particularly to the storing of light oils, gasoline and other liquids in a reservoir which are hydraulically removed from the reservoir by feeding a displacement liquid, such as water, into the tank so that the lighter and immiscible oils or gasoline float on the displacement liquid. The stored liquid may be and preferably is removed from the tank by draining it off by gravity through a pipe carried to the top of the tank, and it is important, therefore, that the displacement liquid shall not rise to the stored-liquid outlet else the water would follow the oil out through the oil delivery pipe when the oil supply is exhausted in the tank. It is also equally important that the water be prevented from receding below a predetermined level in the tank so that the oil will not pass out of the tank through the water outlet pipe through which the water flows when the tank is being filled with oil.

By way of explanation and brevity, the term oil used in the description and claims means any stored liquid and water means any displacement liquid.

The storage reservoir 10 is shown to store gasoline, oil or other liquids O. which are immiscible with a displacement liquid and float thereupon. Water is the preferred displacement liquid, inasmuch as it is the cheapest and most readily obtained, as well as hav-

ing a high specific gravity so that oils and gasoline float thereupon. The tank 10 has a stored-liquid outlet pipe 11 connected at the top and in which a valve 12 is provided for controlling the delivery of the oil therefrom. A stored-liquid inlet pipe 13 is also connected at the top of the tank and preferably feeds into the tank at a point a little below the outlet pipe 11. The oil inlet pipe 13 has a 10 control valve 14.

A displacement-liquid or water inlet connection or pipe 17 connects with the bottom of the tank and has an electrically operated valve 18 therein. The tank also has a displacement-liquid or water outlet connection 20 in which is provided an electrically operated valve 21. The water inlet pipe 17 or tank 10 has an inlet or by-pass 22 with a manually operated valve 23 which permits 20 of the inflow of water to the tank independently of the inlet pipe and valve control means 17, 18. An outlet connection or pipe 24 has a valve 25 for discharging water from the tank 10. The two water pipes 22 and 25 24 provide an independent water supply and drain to and from the tank for manual control of water transfer operations, while the pipes 17 and 20 are automatic in water transfer operations.

30 The reservoir or tank 10 has a float box 30 at its top which is considerably smaller than the tank 10 and consequently, the space at the top of the tank is considerably reduced in volume by maintaining the top level of the stored liquid within the float box. In addition, any expansion or contraction of the stored and displacement liquids in the tank as a result of temperature changes amplifies the expansion and contraction by increasing the extent of rise or fall of the level of the stored liquid O and consequently the liquid level control means therein is rendered more sensitive to the expansion and contraction of the liquids in the tank. The reduced volume 45 of space above the liquid in the float box 30 also reduces the volume of gases exhaled out of the tank or in other words, reduces the extent of the breathing. A vent 31 connects the top of the float box 30 with the outer 50 atmosphere.

A float 33 which floats upon the stored liquid O is carried within the float box 30 on a pivot 34 supported in the sides of the float box 30. An arm 35 is carried on the pivot 34 55 which arm is electrically conducting over a portion of its length but is insulated from the pivot 34, tank 10 and other mechanism by the insulator 36. A pair of contacts 37 are positioned adjacent to the arm 35 so that when 60 the float 33 falls as a result of the lowering of the level of the liquid within the tank 10, an electrical circuit 39 is closed between the contacts 37 through the arm 35 by the arm 65 engaging with the contacts 37. Similarly, when the float rises or lifts as a result of the

rise in the level of the liquid in the tank due to temperature or other changes, the electrically conducting arm 35 engages with contacts 38 and closes an electrical circuit 40 through these contacts. The mechanism controlled by the electric circuits 39 and 40 will be described hereinafter.

A second float box 50 is connected with the top of the tank and positioned somewhat below the float box 30. A float 51 which sinks in the stored liquid O and floats in the displacement liquid W, is provided in the float box 50 and is controlled by the level of the displacement liquid in the tank 10 when it reaches the float box. The float 51 is carried upon a pivot 52 carried by the sides of the float box 50. An electrically conducting arm 53 is carried on the pivot 52 which is insulated from the pivot 52 and tank 10 by the insulator 54. A pair of contacts 55 are positioned adjacent to the arm 53 so that the electrical circuit 39 is closed between the contacts and through the arm 53 when the float 51 is in its lower position which position the float assumes when the level of the displacement liquid W in the tank is below the float even though the float is immersed in the stored liquid O since the float is so adjusted that it will not float but sinks in the stored liquid O. The contacts 55 are connected in series with the contacts 37 in the electrical circuit 39 so that the float 51 through the contacts 55 also controls, under certain conditions to be discussed hereinafter, the solenoid 42 and the electrically operated valve 18 in the inlet connection 17 for the displacement liquid W. The valve 18 may then be termed a displacement-liquid inlet valve.

A third float box 58 is connected with the bottom of the tank 10 and a float 59 which sinks in the stored liquid O and floats upon the displacement liquid W, is carried therein upon the pivot 60 passing through and supported by the side wall of the float box. An electrically conducting arm 61 is carried upon the pivot 60 but is insulated therefrom by the insulator 62 as in the other arms 35 and 53. A pair of contacts 63 are positioned adjacent to the arm 61 so that the arm contacts therewith when the float 59 is in its upper position. The float 59 assumes its upper position when it is immersed in the displacement liquid W and falls or sinks and breaks its engagement with the contacts 63 when immersed in stored liquid O to break the electrical connection between the arm 61 and the contacts 63. The float 59 is adjusted so that it sinks in stored liquid O and floats in the displacement liquid W and corresponds in this respect to the float 51. The contacts 63 are connected in series with the contacts 38 in the circuit 40 so that the float 59, under certain conditions which will be discussed hereinafter, also controls the solenoid 45 and the electrically operated valve 21 in the out-

let connection 20 for the displacement liquid W. The valve 21 is therefore a displacement-liquid outlet valve. The electrical circuits 39 and 40 controlling the solenoids 42 and 45 are connected with a source of electrical potential 65 through the switch 66.

Although float boxes 50 and 58 are provided for the floats 51 and 59 respectively at the top and bottom of the tank or reservoir 10, it is clear that such float boxes are not essential parts of the construction but provide convenient receptacles and mountings for the floats. It is essential, however, that the floats be mounted or connected with the tank 10 so that they are responsive to the level of the liquid in the tank to which it is responsive. The float 33 is then means which are responsive to the level of stored liquid O and the floats 51 and 59 are means which are responsive to the level of the displacement liquid W. The arms 35, 53 and 61 controlled by the respective floats 33, 51 and 59 are switching means when taken in conjunction with their coacting contacts 37, 38 and 63 respectively. The switching means as previously described, control the valves 18 and 21 by which displacement liquid W is permitted to flow into or be discharged from the tank 10.

The electrically controlled valves 18 and 21 are shown to be operated and controlled by solenoids 42 and 45 which are merely illustrative of any electrically operated valve which may be utilized to accomplish the same result. In Figure 2 there is shown a valve 70 which is operated by an electric motor mechanism 71 which is well known in the trade and purchasable upon the market and, consequently, its construction will not be described herein. Such a motor operated valve functions more satisfactorily than a solenoid valve inasmuch as the electrical circuit to the motor actuating the valve is broken and the electricity no longer flows when the valve reaches full open position or full closed position, whereas in the solenoid valves 42 and 45, the electric current continues to flow so long as the valves are held open. The continuous flow of the electricity as in the solenoid valves, uses electrical power and therefore is not as economical as the motor operated mechanism 71 and, in addition, the solenoids 42 and 45 tend to become heated when the valve remains open for any extended period which may result in some cases in an unsatisfactory condition. It is sufficient to state with respect to the motor operated valve 70 that upon the respective circuits being closed at the float switches or contacts, the valves are opened and upon the circuits being opened, the respective valves are closed.

The motor operated valve 70, 71 of Figure 2 is also subject to control irrespective of the circuits 39 and 40. This valve by proper switch arrangement may be controlled at will

and consequently function in a manner similar to the manual control of the displacement-liquid or water inlet and outlet connections through the by-pass connections 22 and 24 and their manually operable valves 23 and 25 irrespective of the position of the solenoid valves 18 and 21. It is clear that these by-pass connections are the equivalent of manual opening or closing means for the solenoid valves themselves which form of valve more nearly coincides with the motor actuated valve 70, 71.

It is advantageous also to have the filling of the tank with oil to be automatically controlled so that in case the operator is negligent the oil will not rise above the high oil level HO when the water level has dropped below the level LW and the switch 61, 63 is opened. Opening of the switch 61, 63 opens the circuit 40 and closes the water outlet valve 21, and the valve cannot open even though the circuit is closed at the switch 35, 38 when the oil reaches the high oil level. It is clear therefore that under such condition it is possible to exceed the high oil level HO by continuing to pump or feed oil into the tank which oil would be wasted out of the vent 31 if the operator was not watching for the upward movement of the arm 35 to inform him that the high oil level had been reached and that the oil feed-in valve 14 should be closed.

The feeding in of oil into the tank 10 and the automatic control thereof is accomplished by running a circuit 75 from the switch 66 and including the float switch 35, 38 in series in the circuit. The circuit 75 connects with the electro-magnet 76 which controls the switch 77 in the motor circuit 78 to the motor 79 driving the pump 80. This circuit then begins from the switch 66 and through the float switch 35, 38 after which it branches through the circuit 75 to the electro-magnet 76 and directly back to the switch 66. Now then whenever the float 33 rises due to a high oil level and closes switch 35, 38 irrespective of whether switch 61, 63 is open or closed the oil pump motor 79 is automatically stopped. It is clear that an automatic valve such as the valve 70, 71 or 18, 42 could be substituted for the pump 80 and motor 79 and such substitution is particularly suitable when the oil is fed into the tank 10 by gravity.

In operating the storage system, the storage tank 10 is first filled with water W and to accomplish this, the switch 66 connected to the source of electrical potential 65 is closed. The tank is completely empty at this stage and consequently the float 33 will be in its lowermost position which closes the circuit 39 through the contacts 37 and arm 35. The float 51 will also be in its lowermost position thereby closing the circuit 39 through the contacts 55 and arm 53 which are in series with the contacts 37 so that a completely closed circuit 39 exists through the solenoid

42 which is energized by the electrical current flowing in the closed circuit. With the solenoid 42 energized, the valve 18 opens against the tension of the spring 43 and the water flows into the tank 10 through the water inlet connection 17. When the level of the water W reaches the float 59 this float is raised thereby. The switching means 61, 63 controlled by this float is in the circuit 40 connected to the solenoid 45 but this circuit is open at the switching means 35, 38 since its controlling float 33 is down and consequently the valve 21 remains closed and the water continues to flow into the tank. The closing of the switching means 61, 63 at this stage has then no effect on the system.

Now when the water W rises to a level so that the float 51 is floated and raised, which is accomplished when the water reaches the high water level HW shown by the dot and dash line at the top of the tank, the arm 53 drops away from the contacts 55 breaking the circuit 39 so that the solenoid 42 is de-energized and the spring 43 closes the valve 18. Closing of the valve 18 stops the flowing-in of water. It will be clear therefore, that the water cannot exceed a higher level than that determined by the float 51 and shown as level HW.

30 The valve 14 in the oil inlet line 13 is now opened so that oil O flows into the tank 10 through the inlet line 13. This oil O floats upon the surface of the water W and when it reaches the level HO which is the high level 35 for the stored liquid or oils, the arm 35 drops and breaks its engagement with the contacts 37 thereby opening the switching means 35, 37. The opening of the switching means 35, 37 has no effect since the circuit 39 is already broken at the switching means 53, 55.

With the oil O continuing to flow into the tank 10 the float 33 continues to rise and shortly after the switching means 35, 37 is opened the switching means 35, 38 is closed. As previously discussed, the switching means 61, 63 is closed so that closing of switching means 35, 38 completes the electrical circuit 40 and the solenoid 45 is energized which opens the water outlet valve 21 against the tension of the spring 46 and the water W flows out through the outlet connection 20 and valve 21 as the oil flows into the tank. The valve 21 remains open so long as the float 33 is raised sufficiently to maintain the switching means 35, 38 in closed position.

With the oil O flowing into the tank 10 through the inlet line 13, it is important that the water W flow out through the water outlet connection 20 at a rate at least as fast as the oil flows in, in order to prevent flooding of the tank. This result is readily accomplished by having the oil inlet 13 no larger than the water outlet connection 20 and pref-

erably it should be somewhat smaller in order to assure against flooding of the tank.

The water W continues to flow out through the outlet connection 20 and the oil O continues to flow into the storage tank 10 through the inlet 13 until the water reaches the low water level LW in the tank. As previously mentioned, the float 59 floats on the water W but sinks in the oil O so that when the water reaches the low water level LW, the float 59 drops, thereby raising the arm 61 and breaking the electrical connection between the contacts 63 through the arm. The solenoid 45 is deenergized and the spring 46 closes the valve 21. The valve 14 should then be closed or closed when the operator notes the arm 35 dropping in order to prevent flooding of the tank.

The control of the inflow of oil is also automatic to prevent flooding of the tank when the circuit 75 is introduced into the storage system. With this circuit the pump 80 is automatically stopped or instead if an automatic valve is provided as mentioned herein, when the oil reaches high oil level HO. This automatic control operates as follows, the oil reaching the float 33 raises the same and closes the switch contacts 35, 38. As previously described this switch controls the circuit 40 and the valve 21 but in addition, this switch 35, 38 controls also the circuit 75 so that a circuit is closed from the switch 66 through the switch 35, 38 and circuit 75 to the solenoid 76 and then back to the switch 66. Solenoid 76 is energized thereby which opens the switch 77 to the motor 79 driving the pump 80 and stops the pump so that the feeding in of oil is discontinued. In a gravity feed system an automatic valve such as valve 70, 71 or 21, 45 can be utilized to shut off the inflow of oil.

The tank 10 may also be filled in the following manner. The by-pass valve 23 in the outlet by-pass connection 22 is opened so that the water flows into the tank. The operator watches the level of the water until it reaches the level HW at which time he closes the by-pass valve 23. The downward movement of the arm 53 offers one means of determining when the level HW is reached. The outlet by-pass valve 25 in the by-pass connection 24 is then opened and the valve 14 is also opened so that the water flows out of the tank as it is being filled with oil. The movement of the arm 61 will inform the operator when the low water level LW for the water W has been reached at which time the outlet by-pass valve 25 is closed. The level of the water should be slightly above the low water level LW so that the float 59 will keep the arm 61 in engagement with the contacts 63 and thereby close the electrical circuit 40 at this point. Similarly, movement of the arm 35 will inform the operator when the oil has reached its high oil level 130

HO at which time the valve 14 is closed. The level of the oil should be such that the arm 35 is not engaging either of the contacts 37 or 38 but is somewhere between these contacts. The automatic control of the pump 80 and the inflow of oil as previously described, provides a completely automatic storage system which does not require the constant attention of an operator.

10 For purposes of convenience in illustration and description, the solenoid operated valves 18 and 21 with the inlet by-pass connection 22 and the inlet by-pass valve 23 in this connection for by-passing the valve 18 15 as well as the outlet by-pass connection 24 with the by-pass outlet valve 25 in this connection for by-passing the valve 21 has been shown, but in the actual commercial construction, the solenoid valves 18 and 21 with their 20 by-pass valves 23 and 25 are substituted by the motor actuated valves 70, 71. This electric motor operated valve 70, 71 may be so controlled by switching mechanism manufactured by the same company who manufactures the valve itself, that the valve 70 25 may be opened or closed at will which is the equivalent of the manually operated by-pass valves 23 and 25 for by-passing the electrically operated valves 18 and 21. By this same 30 switching mechanism the valves 70, 71 may be switched to an automatic connection so that the valve functions automatically in the same manner that the solenoids 42 and 45 with the float controlled switches automatically operate the valves 18 and 21 in a manner which will be described.

In the non-breathing action of the storage system, the manner in which the liquid level is maintained substantially fixed in 40 the tank 10 irrespective of changes resulting from liquid transference, temperature or other causes, will now be described. As previously described, the arm 61 is in engagement with the contacts 63 so that the electrical circuit 40 is closed at this point. It has also been previously mentioned that the arm 35 is out of engagement with either 45 of the contacts 37 or 38. The float 51 being immersed in oil O sinks and closes the electrical circuit 39 at this point through the contacts 55 and arm 33. Assuming now that the temperature rises so that the liquids within the storage tank 10 expand, thereby raising the level of the liquid therein, the float 55 50 33 rises with the rising level of the liquid and closes the electrical circuit between the contacts 38 by the arm 35 engaging these contacts. This completes electrical circuit 40 so that the solenoid 45 is energized and the valve 21 is opened and the water W then flows out through the outlet connection 20 until the level of the liquid drops. The float 33 falls 55 with the dropping liquid level and breaks the electrical circuit 40 at the contacts 38. 60 This opens the electrical circuit 40 and the

solenoid 45 is deenergized so that the spring 46 closes the valve 21. It is clear that if the liquid continues to expand, the above described action repeats itself.

If now the liquids in the storage tank 10 contract, as usually occurs by cooling of the liquids in the tank with the cooling of the air surrounding the tank during the night time, the upper level of the liquid within the tank is lowered and the float 33 drops with the liquid level so that the switch blade or arm 35 engages the contacts 37 and closes the electrical circuit 39. As previously mentioned, the circuit 39 is already closed through the contacts 55 and arm 53. Closing of the electrical circuit 39 through the contacts 37 energizes the solenoid 42 which opens the valve 18 and water flows into the storage tank 10 through the water inlet connection 17. The flowing in of the water raises the level of the liquid in the tank until the float 33 rises sufficiently to break the engagement of the arm 35 with the contacts 37 which opens the electrical circuit 39 and the solenoid 42 is deenergized so that the spring 43 closes the valve 18. It is clear that if the liquids within the storage tank 10 continue to contract, the operation just described will repeat itself as often as may be necessary to maintain the liquid at a substantially constant level within the tank, namely, at the high oil level HO. Maintaining the level of the liquid within the storage tank 10 at a substantially constant level, practically eliminates breathing of the tank and the loss of evaporated stored liquid from the tank.

The storage system also functions as a safety and automatic system in withdrawing the oil from the tank. In order to withdraw the stored liquid or oil, the valve 12 is opened and the oil flows out through the oil outlet 11. The oil flowing out of the tank lowers the liquid level and the float 33 falls with the falling liquid level. The dropping float 33 brings the arm 35 into engagement with the contacts 37 which closes the electrical circuit 39 and energizes the solenoid 42 as previously described. The valve 18 is opened upon the energization of the solenoid 42 and water W flows into the tank through the inlet connection 17 so that the level of the oil will not fall below the outlet connection 11 at the top of the tank. If now the valve 12 is closed, the water W will continue to flow into the tank until the float 33 is raised and breaks the electrical circuit 39 at the contacts 37 which deenergizes the solenoid 42 and the valve 18 closes by the action of the spring 43. It will be observed therefore, that the oil is automatically maintained at the top of the tank so that it may be withdrawn therefrom at any time and so that its level will not fall below the oil outlet 11 at the top of the tank.

If all of the stored liquid or oil O is to be withdrawn from the tank, the oil outlet valve 12 is opened which automatically opens the valve 18, as previously described, so that 5 water W is continually flowing into the tank through the inlet connection 17 so long as the oil outlet valve 12 is open and oil is flowing from the tank. The water continues to flow into the tank until the level of the 10 water reaches the high water level HW at which level the float 51 rises since this float sinks in the oil O but floats upon the water W. The raising of the float 51 breaks the electrical circuit 39 at the contacts 55 which 15 deenergizes the solenoid 42 and the valve 18 in the water inlet connection closes under the influence of the spring 43. The level of the water W is therefore prevented from going higher than or exceeding the high water 20 level HW and, consequently, it will not be possible to draw off water through the oil outlet 11.

When the tank 10 is filled with oil and the water outlet valve 21 is automatically opened 25 so that the level of the water reaches the low water level LW, the float 59 which floats on the water but sinks in the oil or stored liquid, falls with the dropping level of the displacement liquid or water and breaks or opens the 30 electrical circuit 40 at the contacts 63. With the electrical circuit 40 open, the solenoid 45 is deenergized and the spring 46 closes the valve 21 so that further outflow of water through the outlet connection 20 ceases. It 35 will be seen, therefore, that the level of the water is automatically prevented from receding below a predetermined low water level LW and, consequently, it will not be possible for the oil to be wasted out through 40 the outlet connection 20 for the water.

The invention has then, automatic control 45 for maintaining the level of the liquid in the tank at a substantially constant predetermined level irrespective of expansion and contraction of the liquids in the tank due to temperature changes or to changing levels because of liquid transference to or from the tank or because of other causes. Again the level of the water is automatically prevented 50 from exceeding a predetermined level and automatically prevented from receding below a predetermined level during the hydraulic filling or discharging of the oil or water from the tank. Then too the feeding 55 in of oil into the tank is automatically controlled so that flooding of the tank cannot occur.

I claim:

1. A liquid storage system comprising a 60 tank, at least one stored-liquid connection therewith, a displacement-liquid inlet connection with the tank, a displacement-liquid outlet connection at the bottom of the tank, a valve in the inlet connection, a valve in 65 the outlet connection, an electrical actuating

means operatively connected to each valve, a float positioned adjacent the top of the tank and which floats on the upper surface of the stored liquid and is controlled by the movement of said surface, and electrical 70 switch means interconnected between the float and the electrical actuating means for opening and closing said valves to regulate the inflow and outflow of displacement liquid to maintain the upper surface of the stored liquid at a substantially predetermined level in the tank. 75

2. A liquid storage system comprising a tank, at least one stored-liquid connection therewith, a displacement-liquid inlet connection with the tank, a displacement-liquid outlet connection into the tank proximate the bottom thereof, a valve in the inlet connection, a valve in the outlet connection, electrical actuating means for the valves, a float 80 resting on the upper surface of the stored liquid and controlled by up and down movement of the surface, an arm connected to the float and movable therewith, switch means closed by the arm when the float rises and connected with the electrical actuating means for the valve in the outlet connection for opening said valve to permit displacement liquid to flow out of the tank, and switch means closed by the arm when the float falls 85 and connected with the electrical actuating means for the valve in the inlet connection for closing said valve to permit displacement liquid to flow into the tank. 90

3. A liquid storage tank system and means 95 to maintain the upper surface of the stored liquid at a substantially constant level and the displacement liquid within at least one limiting level comprising a tank, a displacement-liquid inlet and a displacement-liquid outlet connection with the tank, a valve in the inlet connection to admit displacement liquid in event the stored-liquid level has a tendency to lower in the tank, a valve in the outlet to drain off displacement liquid in event the stored-liquid level tends to rise in the tank, a system of float-control means including a float which floats on the stored liquid and positioned at the stored-liquid level, and a float 100 which sinks in the stored liquid but floats on displacement liquid and positioned at one of the limiting levels for the displacement liquid, and means interconnected between the system of floats and the valves for opening and closing said valves to maintain the stored-liquid at a substantially constant level excepting when the displacement liquid is 105 at one of its limiting levels. 110

4. A liquid storage tank system and means 115 to maintain the upper surface of the stored liquid at a substantially constant level and the displacement liquid within at least one limiting level comprising a tank, a displacement-liquid inlet and a displacement-liquid outlet connection with the tank, a valve in 120

the inlet connection to admit displacement liquid in event the stored-liquid level has a tendency to lower in the tank, a valve in the outlet to drain off displacement liquid in event the stored-liquid level tends to rise in the tank, a system of float control means including a float which floats on the stored liquid and positioned at the stored-liquid level, and a float which sinks in the stored liquid but floats on the displacement liquid and positioned at one of the limiting levels for the displacement liquid, and electrically operated means interconnected between the system of floats and the valves for opening and closing said valves to maintain a substantially constant stored-liquid level aforesaid excepting when the displacement liquid is at one of its limiting levels.

5. A liquid storage system comprising a tank, fill and delivery pipes connected with the tank for filling and drawing off the liquid to be stored, displacement-liquid inlet and outlet pipes connected with the tank through which liquid flows to and from the tank to maintain the upper surface of the stored liquid at substantially a constant level, motor-actuated valve means in the inlet and outlet pipes, an electric circuit connected with the motor-actuated valve means, switch means included in the electric circuit, and float means in the tank operatively connected with the switch means by which a change in elevation of the surface of the stored liquid acts through the float means to operate the motor-actuated valve means either to admit or drain off the displacement liquid to maintain the constant level.

6. A liquid storage tank system comprising a tank, at least one stored liquid connection therewith, a displacement liquid inlet and a displacement liquid outlet connection with the tank, a valve in the inlet connection, a valve in the outlet connection, a first float positioned adjacent the top of the tank which floats on the upper surface of the stored liquid and is controlled by the up and down movement thereof, a second float which floats in the displacement liquid but sinks in the stored liquid and is controlled by the up and down movement of the liquids in the tank, said second float being adjacent the top of the tank and positioned below the first float, and means interconnected between the floats and the valves for opening and closing said valves to maintain the upper surface of the stored liquid at a substantially predetermined level and to prevent the upper surface of the displacement liquid from exceeding a predetermined level.

7. A liquid storage tank system comprising a tank, at least one displacement-liquid inlet connection therewith, a displacement-liquid outlet connection with the tank, a valve in the inlet connection, a valve in the outlet connection, a first float adjacent the top of the tank

which floats on the surface of the stored liquid and being controlled by the change in level of said surface, a second float which floats on the displacement liquid but sinks in the stored liquid and being controlled by the change of liquid level in the tank, said second float being positioned adjacent the top of the tank and below the first float, means interconnected between the first float and each valve for opening and closing said valves to maintain the stored liquid at a substantially predetermined level, and means interconnected with the second float and the inlet connection valve to prevent the displacement liquid from exceeding a predetermined level.

8. A liquid storage tank system comprising a tank, at least one stored liquid connection therewith, a displacement-liquid inlet and a displacement-liquid outlet connection with the tank, a valve in the inlet connection, a valve in the outlet connection, a first float which floats on the stored liquid and is controlled by the up and down movement of the upper surface of the liquid in the tank, a second float which floats on the displacement liquid but sinks in the stored liquid and is controlled by the up and down movement of the liquid in the tank, said second float being positioned below the first float, electrical actuating means to operate both valves, switch means controlled by the first float and connected with the electrical actuating means of both valves for opening and closing said valves to maintain the upper surface of the stored liquid at a substantially predetermined level, and switch means controlled by the second float and connected with the electrical actuating means for the valve in the inlet connection and in series with the switch means for the first float to prevent the displacement liquid from exceeding a predetermined level.

9. A liquid storage tank system comprising a tank, at least one stored-liquid connection therewith, a displacement-liquid inlet connection and a displacement-liquid outlet connection with the tank, a valve in the inlet connection, a valve in the outlet connection, a first float adjacent the top of the tank which floats on the stored liquid upper surface and is controlled by change in level thereof, another float which floats on the displacement liquid but sinks in the stored liquid and is controlled by movement of the liquid in the tank, said other float being positioned adjacent the bottom of the tank, and means interconnected between the floats and the valves for opening and closing said valves to maintain the stored liquid upper surface at a substantially predetermined level and to prevent the displacement liquid from receding below a predetermined low level.

10. A liquid storage tank system comprising a tank, at least one stored-liquid connection therewith, a displacement-liquid inlet

- and a displacement-liquid outlet connection with the bottom of the tank, a valve in the inlet connection, a valve in the outlet connection, a first float adjacent the top of the tank 5 which floats on the stored liquid upper surface and is controlled by change in level thereof, another float which floats on the displacement liquid but sinks in the stored liquid, said other float being positioned adjacent the bottom of the tank, means interconnected between the first float and both valves for opening and closing said valves to maintain the stored liquid upper surface at a substantially predetermined level, and means interconnected 10 between the float at the bottom of the tank and the valve in the outlet connection to prevent the displacement liquid from receding below a predetermined level. 11. A liquid storage tank system comprising a tank, at least one stored-liquid connection therewith, a displacement-liquid inlet and a displacement-liquid outlet connection made at the bottom of the tank, a valve in the inlet connection, a valve in the outlet connection, a first float adjacent the top of the tank which floats on the stored liquid surface and is controlled by change in level thereof, another float which floats on the displacement liquid but sinks in the stored liquid, the last 15 named float being positioned proximate the displacement-liquid connection at the bottom of the tank, electrical actuating means to operate both valves, switch means controlled by the first float and connected with the electrical actuating means of both valves for opening and closing said valves to maintain the stored liquid upper surface at a substantially predetermined level, and switch means controlled by the other float and connected 20 with the electrical actuating means for the valve in the displacement-liquid outlet connection and in series with the switch for the first float to prevent the displacement liquid from receding below a predetermined level. 12. A liquid storage system comprising a tank, at least one stored-liquid connection therewith, a displacement-liquid inlet connection and a displacement liquid outlet connection at the bottom of the tank, a valve in the 25 inlet connection, a valve in the outlet connection, a first float proximate the top of the tank and which floats on the stored liquid, a pair of floats which sink in the stored liquid but float on the displacement liquid, one of said pair of floats being positioned adjacent the top of the tank but below the first float and the other float being positioned adjacent the bottom of the tank, and means interconnected between the floats and the valves for 30 opening and closing said valves to maintain the stored liquid upper surface at a substantially predetermined level and to prevent the displacement liquid from exceeding a predetermined high level and from receding below a predetermined low level. 13. A liquid storage system comprising a tank, at least one stored-liquid connection therewith, a displacement-liquid inlet connection and outlet connection with the bottom of the tank, a valve in the inlet connection, a valve in the outlet connection, a first float at the top of the tank which floats on the stored liquid, a pair of floats which sink in the stored liquid but float on the displacement liquid, one of said pair of floats being positioned proximate the top of the tank but below the first float and the other float being positioned adjacent the bottom of the tank, means interconnected between the first float and both valves for opening and closing said valves to maintain the stored liquid upper surface at a substantially predetermined level, and means interconnected between the pair of floats, and the first float and both valves to prevent the displacement liquid upper surface from exceeding a predetermined high level and from receding below a predetermined low level. 14. A liquid storage system comprising a tank, at least one stored-liquid connection proximate the top of the tank, a displacement-liquid inlet connection and outlet connection at the bottom of the tank, a valve in the inlet connection, a valve in the outlet connection, a first float which floats on the stored liquid, a pair of floats which sink in the stored liquid but float on the displacement liquid, one of said pair of floats being a high level float and positioned below the first float, the other float being a low level float and positioned adjacent the bottom of the tank, means interconnected between the first float and the valves for opening and closing said valves to maintain the stored-liquid upper surface at a substantially predetermined level, means interconnected between the high level float and the first float and the inlet valve to prevent the displacement liquid from exceeding a predetermined high level, and means interconnected between the low level float and the first float and the outlet valve to prevent the displacement liquid upper surface from receding below a predetermined low level. 15. A liquid storage system comprising a tank, stored-liquid connection means therewith to fill the tank and draw off the stored liquid, a displacement-liquid inlet connection at the bottom of the tank, a displacement-liquid outlet connection at the bottom of the tank, a valve in the inlet connection, a valve in the outlet connection, electrical actuating means for the valves, a first float which floats on the stored liquid, a pair of floats which sink in the stored liquid but float on the displacement liquid, one of said pair of floats being positioned below the first float and the other float being positioned adjacent the bottom of the tank, switch means interconnected between the floats and the electrical actuating means.

means for opening and closing the valves to maintain the stored liquid upper surface at a substantially predetermined level and to prevent the displacement liquid from exceeding a predetermined high level and receding below a predetermined low level.

16. A storage system for oil comprising a storage tank above the ground, a pipe connected proximate the top of the tank to fill and deliver oil to and from the top of the tank, conduit means proximate the bottom of the tank to fill and deliver water to and from the bottom of the tank under the oil, valve means in the conduit means by which the flow of water to and from the tank is controlled; motor means operatively connected with the valve means; three floats two of which are proximate the top of the tank, one of the two floats adapted to normally float on the surface of the oil but the other float normally sinks in oil; the third float being located at the bottom of the tank and normally floats in water, and electrical circuit and switch means interconnected between the three floats and valve means to maintain the upper surface of the oil against the top of the tank and to prevent the upper surface of the water from reaching either top or bottom of the tank.

17. A liquid storage system comprising a tank, an oil connection therewith to fill the tank and draw off the oil, a water inlet connection at the bottom of the tank, a water outlet connection at the bottom of the tank, a valve in the inlet connection, a valve in the outlet connection, electrical actuating means for the valves, a first float which floats on the oil positioned at the top of the tank, a second float which sinks in stored oil and floats on water positioned at the top of the tank but below the first float, a third float which sinks in oil and floats on water positioned at the bottom of the tank, a pair of switches controlled by the first float, one of said pair of switches being closed upon upward movement of the first float with a rising liquid surface in the tank and connected to the actuating means for the valve in the outlet connection, the other switch being closed upon downward movement of the first float with a lowering liquid surface in the tank and connected to the actuating means for the valve in the inlet connection, a switch controlled by the second float and connected in series with the lowering liquid surface switch of the first float, means connecting the lowering liquid surface switch with the actuating means for the inlet valve, and means connecting the rising liquid surface switch with the actuating means for the outlet valve.

18. A liquid storage system comprising a tank, an oil connection therewith to fill the

tank and draw off the oil, a water inlet connection at the bottom of the tank, a water outlet connection at the bottom of the tank, a valve in the inlet connection, a valve in the outlet connection, electrical actuating means for the valves, a float box projecting above the top of the tank, a first float which floats on the stored liquid positioned within the float box, a second float which sinks in stored oil and floats on water positioned at the top of the tank but below the first float, a third float which sinks in oil and floats on water positioned at the bottom of the tank, a pair of switches controlled by the first float, one of said pair of switches being closed upon upward movement of the first float with a rising liquid surface in the tank and connected to the actuating means for the valve in the outlet connection, the other switch being closed upon downward movement of the first float with a lowering liquid surface in the tank and connected to the actuating means for the valve in the inlet connection, a switch controlled by the second float and connected in series with the lowering liquid surface switch of the first float, a switch controlled by the third float and connected in series with the switch rising liquid surface switch of the first float, means connecting the lowering liquid surface switch with the actuating means for the inlet valve, and means connecting the rising liquid surface switch with the actuating means for the outlet valve.

19. A liquid storage system comprising a tank, an oil connection therewith to fill the tank and draw off the oil, a water inlet connection at the bottom of the tank, a water outlet connection at the bottom of the tank, a valve in the inlet connection, a valve in the outlet connection, electrical motor actuating means for the valves, a first float which floats on the oil positioned at the top of the tank, a second float which sinks in stored oil and floats on water positioned at the top of the tank but below the oil outlet, a third float which sinks in oil and floats on water positioned at the bottom of the tank, a pair of switches controlled by the first float, one of said pair of switches being closed upon upward movement of the first float with a rising liquid surface in the tank and connected to the actuating means for the valve in the outlet connection, the other switch being closed upon downward movement of the first float with a lowering liquid surface in the tank and connected to the actuating means for the valve in the inlet connection, a switch controlled by the second float and connected in series with the lowering liquid surface switch of the first float, a switch controlled by the third float and connected in series with the rising liquid surface switch of the first float, means connecting the lowering liquid surface switch with the actuating means for the valve in the inlet connection, a switch controlled by the second float and connected in series with the lowering liquid surface switch of the first float, a switch controlled by the third float and connected in series with the rising liquid surface switch of the first float, means connecting the lowering liquid surface switch with the motor actuating means for the inlet valve, means connecting

- the rising liquid surface switch with the motor actuating means for the outlet valve, and manual means to control the motor actuated means to open or close each valve independently of the float controlled switches. 70
20. A liquid storage system comprising a tank, at least one stored-liquid connection therewith, a displacement-liquid inlet connection with the tank, a displacement-liquid outlet connection at the bottom of the tank, a valve in the inlet connection, a valve in the outlet connection, an electrical actuating means operatively connected to each valve, a float positioned adjacent the top of the tank and which floats on the upper surface of the stored liquid and is controlled by the movement of said surface, electrical switch means interconnected between the float and the electrical actuating means for opening and closing said valves to regulate the inflow and outflow of displacement liquid to maintain the upper surface of the stored liquid at a substantially predetermined level in the tank, and means to automatically stop the feeding in of stored liquid into the tank when the high stored liquid level is reached. 80
21. A liquid storage system comprising a tank, at least one stored-liquid connection therewith, a displacement-liquid inlet connection with the tank, a displacement-liquid outlet connection at the bottom of the tank, a valve in the inlet connection, a valve in the outlet connection, an electrical actuating means operatively connected to each valve, a float positioned adjacent the top of the tank and which floats on the upper surface of the stored liquid and is controlled by the movement of said surface, electrical switch means interconnected between the float and the electrical actuating means for opening and closing said valve to regulate the inflow and outflow of displacement liquid to maintain the upper surface of the stored liquid at a substantially predetermined level in the tank, and means controlled by the float to automatically stop the feeding in of stored liquid into the tank when the rising stored liquid raises the float. 90
22. A liquid storage system comprising a tank, at least one stored-liquid connection therewith, a displacement-liquid inlet connection with the tank, a displacement-liquid outlet connection at the bottom of the tank, a valve in the inlet connection, a valve in the outlet connection, an electrical actuating means operatively connected to each valve, a float positioned adjacent the top of the tank and which floats on the upper surface of the stored liquid and is controlled by the movement of said surface, electrical switch means interconnected between the float and the electrical actuating means for opening and closing said valves to regulate the inflow and outflow of displacement liquid to maintain the upper surface of the stored liquid at a sub- 100
- stantially predetermined level in the tank, and electrical means controlled by the switch means to automatically stop the feeding in of oil into the tank when the oil level raises the float. 105
23. A liquid storage tank system comprising a tank, at least one stored liquid connection therewith, a displacement-liquid inlet and a displacement-liquid outlet connection with the tank, a valve in the inlet connection, a valve in the outlet connection, a first float which floats on the stored liquid and is controlled by the up and down movement of the upper surface of the liquid in the tank, a second float which floats on the displacement liquid but sinks in the stored liquid and is controlled by the up and down movement of the liquid in the tank, said second float being positioned below the first float, electrical actuating means to operate both valves, switch means controlled by the first float and connected with the electrical actuating means of both valves for opening and closing said valves to maintain the upper surface of the stored liquid at a substantially predetermined level, switch means controlled by the second float and connected with the electrical actuating means for the valve in the inlet connection and in series with the switch means for the first float to prevent the displacement liquid from exceeding a predetermined level, and means controlled by the switch means of the first float to automatically shut off the inflow of stored liquid when the liquid raises the float. 110
24. A liquid storage tank system comprising a tank, at least one stored-liquid connection therewith, a displacement-liquid inlet and a displacement-liquid outlet connection made at the bottom of the tank, a valve in the inlet connection, a valve in the outlet connection, a first float adjacent the top of the tank which floats on the stored liquid surface and is controlled by change in level thereof, another float which floats on the displacement liquid but sinks in the stored liquid, the last named float being positioned proximate the displacement-liquid connection at the bottom of the tank, electrical actuating means to operate both valves, switch means controlled by the first float and connected with the electrical actuating means of both valves for opening and closing said valves to maintain the stored liquid upper surface at a substantially predetermined level, switch means controlled by the other float and connected with the electrical actuating means for the valve in the displacement-liquid outlet connection and in series with the switch for the first float to prevent the displacement liquid from receding below a predetermined level, and means controlled by the switch means of the first float to automatically shut off the inflow of stored liquid when the liquid raises the float. 120
25. A liquid storage system comprising a tank, at least one stored-liquid connection therewith, a displacement-liquid inlet connection with the tank, a displacement-liquid outlet connection at the bottom of the tank, a valve in the inlet connection, a valve in the outlet connection, an electrical actuating means operatively connected to each valve, a float positioned adjacent the top of the tank and which floats on the upper surface of the stored liquid and is controlled by the movement of said surface, electrical switch means interconnected between the float and the electrical actuating means for opening and closing said valves to regulate the inflow and outflow of displacement liquid to maintain the upper surface of the stored liquid at a sub- 125
- stantially predetermined level in the tank, and electrical means controlled by the switch means to automatically stop the feeding in of oil into the tank when the oil level raises the float. 130

25. A liquid storage system comprising a tank, an oil connection therewith to fill the tank and draw off the oil, a water inlet connection at the bottom of the tank, a water
5 outlet connection at the bottom of the tank, a valve in the inlet connection, a valve in the outlet connection, electrical actuating means for the valves, a first float which floats on the oil positioned at the top of the tank,
10 a second float which sinks in stored oil and floats on water positioned at the top of the tank but below the first float, a third float which sinks in oil and floats on water positioned at the bottom of the tank, a pair of
15 switches controlled by the first float, one of said pair of switches being closed upon upward movement of the first float with a rising liquid surface in the tank and connected to the actuating means for the valve in the
20 outlet connection, the other switch being closed upon downward movement of the first float with a lowering liquid surface in the tank and connected to the actuating means for the valve in the inlet connection, a switch
25 controlled by the second float and connected in series with the lowering liquid surface switch of the first float, a switch controlled by the third float and connected in series with the switch rising liquid surface switch
30 of the first float, means connecting the lowering liquid surface switch with the actuating means for the inlet valve, means connecting the rising liquid surface switch with the actuating means for the outlet valve, and
35 means controlled by the rising liquid surface switch of the first float to automatically shut off the inflow of stored liquid when the liquid raises the float.

In testimony whereof I affix my signature.
40 WILLIAM J. PETER.
